UNITED STATES PATENT OFFICE.

THOMAS P. J. LENNON, OF ROXBURY, MASSACHUSETTS.

MUSIC-LEAF TURNER.

1,174,877.

Specification of Letters Patent. Patented Mar. 7, 1916.

Application filed July 3, 1915. Serial No. 37,846.

To all whom it may concern:

Be it known that I, THOMAS P. J. LENNON, a citizen of the United States, residing at Roxbury, in the county of Suffolk, 5 State of Massachusetts, have invented certain new and useful Improvements in Music-Leaf Turners; and I do hereby declare the following to be a full, clear, and exact description of the invention, such as 10 will enable others skilled in the art to which it appertains to make and use the same.

This invention relates to music leaf turners.

The object of the invention is to provide 15 a music leaf turner embodying an adjustable standard having a depending arm upon which latter is rotatably mounted a turning disk. This disk is provided with a radial slot and depending page clip. A rotatable 20 shaft is also provided having a lateral arm the free end of which is engaged in the radial slot whereby rotation of the shaft will effect rotation of the turning disk.

In the drawings chosen to illustrate the 25 invention, the scope whereof is pointed out in the claims—

Figure 1 is a view in elevation of a music leaf turner constructed in accordance with the invention; Fig. 2, a top view of same; 30 Fig. 3, a view similar to Fig. 2 showing the leaf of the music turned; Fig. 4, a perspective view of the rotating disk, and Fig. 5, a perspective view looking at a fragment of the bottom of the turning mechanism.

35 Referring to the drawings 10 indicates a music stand upon which is supported a music folio 11 including a loose leaf 12. The stand 10 may be of any desired construction. The leaf turning mechanism

40 comprises a base 13 from which rises a frame 14. Mounted in the frame 14 and extending through the base 13 is a vertical shaft 15 formed of adjustable sections and held in the desired position by the thumb screw 15'.

45 The upper end of the shaft 15 terminates in a lateral arm 16 and the free end of this arm is bent upwardly to form a toe 17. The lower end of the shaft 15 is bent laterally as at 18 and then upwardly as at 19,

50 the upwardly extending portion 19 passing through an arcuate slot 20 in the base 13 arranged concentric with respect to the shaft 15. Under the base 13 is secured the U-shaped member 18' which supports the

arm 18 of the shaft 15. The upper end of 55 the portion 19 carries a foot pedal 21 whereby the shaft 15 may be readily oscillated by the musician while playing. Also mounted in the frame 14 is a vertical rod 22 also formed of adjustable sections held in desired position by the thumb screw 22' and having a laterally directed terminal 23 which supports a depending arm 24. Rotatably mounted on the arm 24 is a disk 25 provided with a radial recess 26 in which 60 is engaged the toe 17. This disk 25 carries a clip 27 adjacent its periphery and this clip is adapted to be secured to the leaf 12.

In the use of the device the turning mechanism is positioned so that the axis of rotation of the disk 25 is coincident with the pivot of the leaf 12. The clip 27 is then secured to the leaf 12 and when it is desired to turn said leaf it is only necessary to place the foot against the pedal 21 and by pushing forward the oscillation of the shaft 15 is caused. This oscillation of the shaft 15 will be transmitted through the toe 17 to the disk 25 and the rotation of the latter will effect the desired turning of the leaf 12. If it is desired to return the leaf 12 to its original position the toe of the operator's foot is placed behind the pedal 21 and by a pull of the foot the shaft 15 will oscillate in the opposite direction. 75 80 85

What is claimed is:—

A music leaf turning device comprising a base, a frame rising from the base, a vertical shaft rotatably mounted in the frame and extending through the base, the lower 90 end of said shaft being directed laterally and then upwardly through an arcuate slot in the base, a pedal on the upper end of the upwardly directed portion of the lower end of the shaft, a vertical rod mounted in the 95 frame, a lateral arm on the upper end of said rod, a disk rotatably supported by said rod and having a radial recess therein, a lateral arm on the upper end of the shaft provided with a toe engaged in said recess, 100 and a leaf engaging clip carried by the disk.

In testimony whereof, I affix my signature, in the presence of two witnesses.

THOMAS P. J. LENNON.
